UNITED STATES PATENT OFFICE.

CHARLES H. BARTLETT, OF ELIZABETH, NEW JERSEY, ASSIGNOR TO ELECTRIC BOAT COMPANY, OF NEW YORK, N. Y., A CORPORATION OF NEW JERSEY.

ENGINE CONSTRUCTION.

1,105,604.

Specification of Letters Patent.

Patented Aug. 4, 1914.

Application filed June 19, 1911. Serial No. 634,063.

To all whom it may concern:

Be it known that I, CHARLES H. BARTLETT, a citizen of the United States, and resident of 911 East Jersey street, Elizabeth, Union county, State of New Jersey, have invented certain new and useful Improvements in Engine Construction; and I do hereby declare the following to be a full, clear, and exact description of the invention, such as will enable others skilled in the art to which it appertains to make and use the same:

This invention relates to engine construction, and particularly to a form of construction especially adapted to single or multiple cylinder internal combustion engines in which the working cylinder of each unit is arranged in tandem with an air-compressing cylinder.

One object of the invention is to provide an engine having a supporting bed-plate or foundation structure, (preferably common to all the cylinders in the case of a multiple cylinder engine) on which the tandem cylinders are separably supported so that the engine may be readily assembled or dismantled without disturbing the bed-plate or foundation structure.

In the preferred construction that portion of the foundation structure which surrounds and supports the compressing cylinder is of such configuration that a closed receiver for the compressed air is formed between the wall of the compressing cylinder and the surrounding support. In engine constructions of this kind heretofore customary, it was usual either to have the foundation structure made integral with one of the cylinders or simply to flange the lower end of the bottom cylinder and bolt it to the foundation structure or bed-plate; so that if the construction was mechanically strong as in the first case, easy assembly and complete dismantling of parts were impossible; while if these features were obtained, as in the second case, the construction was mechanically weak unless an undue amount of metal was used to secure the proper strength.

In the construction herein disclosed as an example, the upper cylinder, usually the working cylinder, is formed in one piece and is flanged and bolted to the other cylinder so as to be readily connected thereto and disconnected therefrom. The foundation structure or bed-plate of the engine carries an

upstanding sleeve or housing into which the compressing cylinder fits, so as to be supported at one end by the bed-plate and also at a point intermediate of its ends by the sleeve or housing, whereby the cylinder may be readily set up or taken down, while it is rigidly supported when in position without the use of an undue amount of metal. Furthermore, the housing and the compressing cylinder form between them a receiver for compressed air, the abutting parts being machined to make a tight fit. This construction may be applied to a vertical or a horizontal engine of any number of cylinder units, wherein each unit may have two cylinders or any other suitable number. Furthermore the engine may work on a two-stroke cycle, or any other cycle wherein explosive gas is ignited by ignition devices, or wherein a vapor of heavy oil is spontaneously ignited by contact with highly compressed air.

The accompanying drawings and description are directed to an engine working on a two-stroke Diesel cycle, and to an engine having six cylinder units, each comprising a working cylinder, and a compressing cylinder of larger diameter, in tandem arrangement; but I do not limit myself to this specific embodiment or to the details of construction, since it will be evident that the essential features of my invention may be applied to various kinds of engines and to various arrangements of the cylinders.

In the drawings, Figure 1 is a central section through one cylinder unit of an engine illustrating a construction of the working and compressing cylinders in accordance with my invention; Fig. 2 is a front view of a six-cylinder engine embodying this construction; and Fig. 3 is a detail view showing the means for admitting compressed air from the receiver to the working cylinder.

The bed-plate or foundation structure is made up of a trough-like structure 1 extending substantially the whole length of the engine, and the part 2 likewise extending the length of the engine, and fastened to the trough-like structure by bolts or in any suitable way (not shown). The part 2 has an upwardly projecting sleeve or housing 3 for each unit into which is fitted the compressing cylinder 4 so as to be supported at 5 and 6. The flange 7 of the compressing cylinder 4 is fastened tightly to the sleeve at 6 by 116

bolts 31, while the joint at 5 is made tight by packing or gaskets, for example, so that the annular space 8 formed between the compressing cylinder 4 and the sleeve 3 is adapted to hold lightly compressed air without leakage thereof to the crank case or to the atmosphere. The working cylinder 9 is fastened by means of a flange 10 and bolts 30 to the top of the compressing cylinder. The 10 working cylinder may be provided with a jacket 11, whereby water or other cooling medium is circulated in the space 12 by any well known means. In each unit the working piston 13 and the compressing piston 14 15 are arranged in echelon in their respective cylinders, and they are connected to the engine shaft 15 in any well known manner such as by the wrist pin 16, pitman 17, crank pin 18, and crank 19. The engine shaft also 20 carries the fly-wheel 32. Any suitable lubricating system may be used.

For a two-stroke Diesel cycle, the operation of the engine during the period of running is as follows: At the proper point of 25 the up-stroke, fuel is admitted into the top of a working cylinder 9 by means of a suitable valve, indicated at 20. Upon combustion of the fuel, the pistons are forced down and at a definite point of the stroke the 30 products of the combustion rush out of the exhaust port 21 into the common exhaust pipe 22. During the period that the exhaust port is uncovered, scavenging air compressed to the proper degree is admitted into the 35 working cylinder by the inlet valve 23 in pipe 24 which leads from the receiver 8. This inlet valve may be mechanically actuated from the engine shaft by a rod 25, or it may be actuated in any other suitable manner. The scavenging air forces the 40 remaining products of combustion from the working cylinder, while that part of the air which is entrapped in the working cylinder upon closure of the exhaust port is compressed during the up-stroke of the engine 45 to a pressure sufficiently high to spontaneously ignite the injected fuel.

During the down movement of the working piston, air from the outside is drawn into 50 the compressing cylinder 4 through the port 33, valve 34, and port 35 while the discharge valve 27 is kept closed by the pressure of the air in the receiver 8 on the other side of the valve. During the up-stroke of the engine 55 the air is lightly compressed in the compressing cylinder, and when its pressure becomes sufficiently high the discharge valve 27 automatically opens and allows the air to pass through port 26, pipe 28 and opening 29 to the receiver 8. During the up-stroke of the compressing piston the inlet valve 34 is kept closed as a result of the pressure on its inside face. This method of operation is well known in the art and need not 60 be further elaborated.

To dismantle any unit of the engine, the exhaust pipe 22 is disconnected from the particular cylinder, the corresponding bolts 30 are removed, the air supply pipe coupling 36 is disconnected and the operating mechanism is disconnected, whereupon the working cylinder may be pulled bodily out of the compressing cylinder. The compressing cylinder may then be taken out after the bolts 31 and pipe 28 have been disconnected. 70 In this way both sets of cylinders may be dismantled without disturbing the foundation structure, and the working cylinders may be dismantled without disturbing the compressing cylinders. 75

Having thus described my invention what I claim is:

1. In an engine construction, a foundation structure including a crank case, an air compressing cylinder, a working cylinder in tandem arrangement with the compressing cylinder, and a supporting housing for the compressing cylinder, an air reservoir or receiver located between the compressing cylinder and housing, connections between the air receiver and working cylinder for admitting compressed air thereto, and a valved connection between the air receiver, and the compressing cylinder. 80

2. In an engine construction, a foundation structure including a crank case, a part arising therefrom and secured thereto, a housing formed integrally with said part and extending outwardly therefrom, an air compressing cylinder located within said housing and forming an air receiver in connection with the latter, connections between the air receiver and working cylinder for admitting compressed air thereto, and a valved connection between the air receiver and the compressing cylinder. 90

3. In an engine construction, a foundation structure including a crank case, a part arising therefrom and secured thereto, a housing formed integrally with said part and extending outwardly therefrom, and an air compressing cylinder located within said housing and forming an air receiver in connection with the latter, the air compressing cylinder being supported by the housing 110 at its lower end and secured to it about midway its length, and valved connections between the air receiver and the working and compressing cylinders whereby free air is compressed in the receiver on one stroke of 115 the piston and discharged therefrom on its succeeding stroke. 120

4. In an engine construction, a plurality of engine units, a trough like structure arranged below said units and extending 125 throughout their length, a part secured to said trough like structure and having formed integrally therewith a housing for each engine unit, and a compressing cylinder in each housing, said housing and com- 130

pressing cylinder forming between them an air receiver adapted to receive and supply compressed air at the proper time in the operation of the engine.

- 5 5. In an engine construction, a plurality of engine units, a trough like structure arranged below said units and extending throughout their length, a part secured to said trough and extending the length of the 10 latter, a housing projecting from the part for each engine unit, a working cylinder for each engine unit, a compressing cylinder for each engine unit, and an air receiver for each engine unit formed by the housing and 15 compressing cylinder, the compressing cylinder being supported by the housings and in turn supporting the working cylinders.
6. In an engine construction, a plurality of engine units, a trough like structure extending under and throughout the length of 20 said units, a part secured to said trough like structure and having a series of housing arising therefrom compressing cylinders locked within and supported by the hous-

ings, an air receiver formed by the compressing cylinder and its containing housing, and means for compressing air in said receiver and delivering it therefrom at predetermined intervals.

7. In an engine construction, a plurality 30 of engine units, a trough like structure extending under and throughout the length of said units, a part secured to said trough and having a series of housings, one for each cylinder unit, compressing cylinders supported at their lower ends by the housings and secured thereto at the upper ends of the latter, and air receivers formed between the compressing cylinders and housings and adapted to receive and discharge compressed 35 air at the proper intervals.

In testimony whereof I affix my signature, in presence of two witnesses.

CHARLES H. BARTLETT.
